UNITED STATES PATENT OFFICE.

PROSPER JULES CHARBONNIER, OF PARIS, FRANCE.

EQUILIBRATED BREECH BLOCK.

Application filed August 2, 1922. Serial No. 579,240.

To all whom it may concern:

Be it known that I, PROSPER JULES CHARBONNIER, a citizen of the Republic of France, and residing at Paris, Seine Department, in the Republic of France, have invented certain new and useful Equilibrated Breech Blocks, of which the following is a specification.

This invention relates to a breech-block having a large surface of contact and a minimum size which remains constant in all positions, as well as a perfect balancing, and is adapted for all calibres without prejudice to its qualities as to safety or facility of operations.

The said breech block is composed of a solid block having two opposite surfaces of revolution whereof one serves for the closing and the other for contact with the breech, the said piece being pivoted on a pair of trunnions whose axis passes substantially through the centre of gravity.

The accompanying drawings which are given by way of example show a breech-block according to the invention.

Fig. 1 is a diagrammatic view of the breech-block in longitudinal section on a plane passing through the axis of the cannon,

Fig. 2 is a front view of the same, and Fig. 3 a plan view in section.

Fig. 4 is a vertical section on a larger scale of the trunnion arrangement of the breech-block.

Figure 5 is a diagrammatic view similar to that of Figure 1 showing the positions of the centers.

1 indicates the breech wherein is formed a recess 2 for inserting the breech-block 3; the latter has a portion with a spherical surface 4 at the front part for closing the cannon and at the rear a portion with surface of revolution 5 bearing upon the breech, the other surfaces being plane.

The whole device is mounted upon the horizontal trunnions 6 and pivots thereupon by means of a lever 7 keyed to a shaft 8 which is secured to a toothed quadrant 9 engaging a like quadrant 10 mounted on the breech-block. To obviate jamming, the said axle is disposed below the centre of the surface 4 and above the centre of the surface 5,

the breech-block being opened by giving it a counter-clockwise rotation, Fig. 1.

Figure 5 shows the position of the centers of the surfaces 4 and 5 and that of the axis about which the breech is pivoting.

It will be seen that the center A of the surface 4 is located above the axis C about which the breech is pivoting, this latter axis being itself arranged above the center B of the surface 5.

Under these conditions, as soon as the breech is moved in the direction of the arrow, for the purpose of opening, it will be observed that the center A comes to A₁ and the center B to B₁ and that the surfaces 4 and 5 assume the positions which are indicated in dash and dotted lines in moving away from the bearing surfaces of the breech-end. Of course, on the drawing, the distances AC and CB have been enlarged; in the reality these distances are very small.

The trunnions 6 are supported upon knife-edges 11 mounted in the breech with a certain amount of play, Fig. 4, and held by springs 12 driving the same forward through the medium of the bearings 12', whereby the breech-block will offer no resistance to the opening at its surface of contact.

For a like purpose, the trunnions 6 are laterally maintained by an elastic device, for example by springs 13. The breech-block is provided with a cylindrical aperture 14 whose axis is vertical when the breech-block is closed and horizontal when open, and in the latter case said aperture is located in the prolongation of the bore of the cannon, and a like aperture 15 is provided at the end of the breech. It is observed that the projectile can thus be introduced, when loading, through the breech-block itself. The movements of the breech-block are limited in either sense by suitable stops such as stop-screws.

Claims:

1. In a gun, a block adapted to be used as a breech, horizontal trunnions on this block arranged at right angle to the axis of the gun and movable in the breech-end, this block having a convex spherical face at the front and a convex revolving surface at the rear, the breech-end having concave bearing surfaces corresponding to the said surfaces,

the axis of the trunnions being placed under the center of the front face of the block and above the center of the rear face so that the opening of the breech produces a rise of its

5 front face.

2. In a gun, a block adapted to be used as a breech, trunnions on this block, knife edged blocks upon which these trunnions rest, these

knife edged blocks being mounted in the gun with a certain play, and springs adapted 10 to press the said knife edged blocks forwardly.

In testimony that I claim the foregoing as my invention, I have signed my name.

PROSPER JULES CHARBONNIER.
